UNITED STATES PATENT OFFICE.

JOHN STORER CONNELLY, OF TITUSVILLE, PENNSYLVANIA.

DESIGN FOR A FRAME FOR REFLECTING-SPECTACLES.

SPECIFICATION forming part of **Design No. 28,887**, dated June 21, 1898.

Application filed September 30, 1897. Serial No. 653,655. Term of patent 14 years.

To all whom it may concern:

Be it known that I, JOHN STORER CONNELLY, of Titusville, in the county of Crawford and State of Pennsylvania, have invented 5 a new and original Design for Frames for Reflecting-Spectacles, of which the following is a full, clear, and exact description, reference being had to the accompanying drawing, which shows in elevation a spectacle-frame embodying my invention.

My invention consists in a frame for reflecting-spectacles, having substantially the shape shown in the accompanying drawing and herein described.

10 15 In the drawing, 2 represents an arch-shaped

bridge-piece at the middle of the frame, having single parts 3 extending in opposite directions therefrom, at the outer ends of which parts 3 are holders 5 for containing the reflecting-surfaces 4.

20

I claim—

The design for a frame for reflecting-spectacles substantially as shown and described.

In testimony whereof I have hereunto set my hand September 29, 1897.

JOHN STORER CONNELLY.
